(57) **CLAIM**

The ornamental design for a laser wire stripping apparatus case, as shown and described.

DESCRIPTION

FIG. 1 is a front perspective view of the laser wire stripping apparatus case, showing my new design;

FIG. 2 is a rear perspective view of the laser wire stripping apparatus case;

FIG. 3 is a top view of the laser wire stripping apparatus case;

FIG. 4 is a front elevational view of the laser wire stripping apparatus case;

FIG. 5 is a left side elevational view of the laser wire stripping apparatus case;

FIG. 6 is a rear elevational view of the laser wire stripping apparatus case;

FIG. 7 is a right side elevational view of the laser wire stripping apparatus case; and,

FIG. 8 is a bottom view of the laser wire stripping apparatus case.
